UNITED STATES PATENT OFFICE.

JAMES L. SMITH, OF PRINCETON, INDIANA.

GATE.

SPECIFICATION forming part of Letters Patent No. 243,318, dated June 21, 1881.

Application filed April 21, 1881. (Model.)

To all whom it may concern:

Be it known that I, JAMES L. SMITH, of Princeton, in the county of Gibson, and in the State of Indiana, have invented certain new and useful Improvements in Gate-Hinges; and I do hereby declare that the following is a full, clear, and exact description thereof, reference being had to the accompanying drawings, and to the letters of reference marked thereon, making a part of this specification.

This invention relates to certain improvements in gates; and it has for its objects to provide a simple and efficient means whereby the gate may be operated and raised and kept at any desired height in case of snow-drifts, or when it is desired to permit small stock to pass freely under the gate to separate the same from larger stock. These objects I attain by the apparatus illustrated in the accompanying drawings, in which—

Figure 1 represents a perspective of my improved gate; Fig. 2, an end elevation thereof, showing the means of hanging it on the gate-post; and Fig. 3 a detached perspective view 25 of the improved hinge by which the gate is hung to the post.

The letter A indicates the post which supports the gate, which is provided with a cylindrical extension, a, at its upper end, and which 30 is secured at its lower end in the ground in the usual manner.

The letter B indicates a thimble-hinge, which is adapted to fit upon the cylindrical portion of the gate-post and turn thereon, resting normally upon the shoulder at the juncture of the cylindrical and lower portion of said post. The 35 said hinge at its lower edge is inclined, as shown at b, and the upper edge of the shoulder of the post is similarly inclined, but in the opposite direction, so that the weight of the

gate will cause the hinge to rotate and close the gate automatically when opened. The said hinge has a slotted extension, c, at one side, and in said slot is located a friction-wheel, d, upon which the upper rail of the gate C is 45 adapted to rest and slide. The cylindrical part of the gate-post at desired intervals is provided with apertures d, and a pin, e, adapted to be inserted in such apertures, by means of which the hinge, and with it the gate, can be 50 elevated to any desired height.

The letter D indicates a hook attached to the gate, which bears against the gate-post A and holds the lower part of the gate to the said post.

E indicates a friction-roller, upon which the lower part of the rail is adapted to travel as the gate slides back and forth.

The post F, which supports the free end of the gate when closed, is provided with a series 60 of seats, G, for the latch H, so that the gate may be held in position corresponding to the elevation of the hinge when it is closed.

The letter I indicates a stop for holding the gate below when closed.

Having thus described my invention, what I claim, and desire to secure by Letters Patent, is—

The combination, with the cylindrical portion of the fence-post, of the adjustable hinge 70 provided with a friction-roller, upon which the gate is adapted to be supported and to slide, substantially as specified.

In testimony that I claim the foregoing I have hereunto set my hand this 13th day of April, 1881.

JAMES L. SMITH.
